[57] **CLAIM**

The ornamental design for a keypad for a game scoring device, as shown and described.

DESCRIPTION

FIG. 1 is a front elevational view of a keypad for a game scoring device showing my new design, the rear being planar and unornamented;

FIG. 2 is a right side elevational view thereof; and FIG. 3 is a reduced perspective view thereof.

The broken lines showing a game scoring device in FIGS. 1, 2, and 3; and the legible indicia in FIGS. 1 and 3 are for illustrative purposes only and form no part of the claimed design.
